United States Patent Office.

J. S. MUNGER, OF OLEAN, NEW YORK.

Letters Patent No. 65,686, dated June 11, 1867.

IMPROVED CARPET-STRETCHER AND HOLDER.

The Schedule referred to in these Letters Patent and making part of the same.

TO ALL WHOM IT MAY CONCERN:

Be it known that I, J. S. MUNGER, of Olean, Cattaraugus county, State of New York, have invented an improved Carpet-Stretcher; and declare that the following is a full, clear, and exact description thereof, reference being had to the accompanying drawings, making part of this specification, in which—

Figure 1 is a bottom view of a carpet-holder with the stretchers applied.

Figure 2 is a top view of the same.

Figure 3 is a side view.

Figure 4 is a view of a lever which may be used in the operation of stretching.

Similar letters of reference indicate corresponding parts in the several figures.

The object of this invention is to facilitate the stretching and fastening of carpets upon floors by the employment of sharp-pointed dogs or holders, which, in conjunction with metal plates that are hooked to the edge or selvedge of the carpet, will firmly hold the latter to the floor and prevent it from retracting or drawing back during the act of stretching and fastening it down, as will be hereinafter described.

To enable others skilled in the art to understand my invention, I will describe its construction and operation. In the accompanying drawings, A represents a strip of metal, which may be made of any suitable length and width, and which is constructed with hooks *a a*, formed on one edge, at suitable distances apart. These hooks are bent under, as shown in figs. 1 and 3, and are designed for fastening the strip securely to the edge of a carpet. At suitable distances apart, along the back edge of the strip A, holes *b b* are made, which are designed to receive through them pins *c*, which are driven into the floor near the wash-board, and thus to hold the strip and the carpet without the use of nails or tacks driven through the carpet, as hitherto practised. Near each end of the hooked holding-strip A an oblong slot is made through it for the purpose of receiving a tongue, *d*, which is formed on the end of a curved dog, B, as shown in figs. 1 and 3. The dogs B are both alike in form and construction. Each one is curved in the form of a bow with two or more divergent sharp-pointed teeth *e e*, formed upon one end, for the purpose of penetrating a carpet and attaching themselves to the floor, so as to prevent the drawing backward of the carpet while it is being stretched. The tongues *d* on the dogs are inserted into the slots which are through the hooked plates A, after this plate is attached to the edge of the carpet. The carpet is then stretched by grasping the two dogs and pressing them forward, at the same time holding their pointed ends down, so that when the pressure is removed these ends will catch into the floor and hold the carpet so as to prevent it from drawing back. By means of these dogs catching into the floor whenever the carpet is released after it has been stretched, the plate A may be gradually worked up to its proper place and hooked on the pins which are fastened into the floor. These dogs B may be made of cast or wrought metal. They should be made strong enough to prevent springing whilst holding the carpet under tension, and they should be made long enough to admit of being conveniently grasped in the hand. I am aware that hooked plates have been used before my invention, for the purpose of holding a carpet upon a floor without the use of tacks and nails, and therefore I do not claim this hooked plate as my invention.

Having described my invention, what I claim as new, and desire to secure by Letters Patent, is—

1. The pointed dogs B, adapted for use in the operation of stretching carpets, and constructed substantially as described.
2. The combination of hooked holding-plates A with curved dogs B, substantially as described.

Witness my hand in the matter of my improved self-holding carpet-stretcher this   day of March, 1867.

J. S. MUNGER.
